UNITED STATES PATENT OFFICE.

EDWARD A. REHBERGER, OF NEWARK, NEW JERSEY.

DESIGN FOR AN AUTOMOBILE RADIATOR TOP.

Application filed January 18, 1924. Serial No. 8,350. Term of patent 14 years.

To all whom it may concern:

Be it known that I, EDWARD A. REHBERGER, a citizen of the United States, residing at Newark, county of Essex, and State of New Jersey, have invented a new, original, and ornamental Design for an Automobile Radiator Top, of which the following description, in connection with the accompanying drawing, is a specification.

The drawing is a perspective view of an

automobile radiator top embodying my new design, which may be manufactured and sold as a separate and complete article.

I claim:—

The ornamental design for an automobile radiator top as shown.

EDWARD A. REHBERGER.
